US00D359110S

United States Patent [19]

Vestergaard

[11] Patent Number: Des. 359,110

[45] Date of Patent: ** Jun. 6, 1995

**[54] THERMOSTATIC EXPANSION VALVE FOR
REFRIGERATING PLANTS**5,026,022 6/1991 Bastle ..... 62/225 X
5,269,459 12/1993 Thompson et al. ..... 236/92 B[75] Inventor: **Anders Vestergaard**, Sydals,
Denmark*Primary Examiner*—A. Hugo Word
Assistant Examiner—Eric Watterson
Attorney, Agent, or Firm—Lee, Mann, Smith,
McWilliams, Sweeney & Ohlson[73] Assignee: **Danfoss A/S**, Nordborg, Denmark[57] **CLAIM**[**] Term: **14 Years**The ornamental design for a thermostatic expansion
valve for refrigerating plants, as shown and described.[21] Appl. No.: **19,131****DESCRIPTION**[22] Filed: **Feb. 23, 1994**FIG. 1 is a perspective view of a thermostatic expansion
valve for refrigerating plants according to my invention;[30] **Foreign Application Priority Data**Aug. 23, 1993 [DE] Germany 93 06 710.0
[52] U.S. Cl. D23/233
[58] Field of Search D23/233-237;
62/225; 236/92 B; 251/285, 61.4, 84

FIG. 2 is a perspective view opposite to that of FIG. 1;
